OF D 13.979

No. 13.979.

June 12. 1883.

UNITED STATES PATENT OFFICE.

JAMES E. KERR, OF PHILADELPHIA, PENNSYLVANIA, ASSIGNOR TO WILLIAM HUNTER & SON, OF SAME PLACE.

DESIGN FOR TWO-PLY UPHOLSTERY.

SPECIFICATION forming part of Design No. 13,979, dated June 12, 1883.

Application filed April 30, 1883. Term of patent 3½ years.

To all whom it may concern:

Be it known that I, JAMES E. KERR, a citizen of the United States, residing at Philadelphia, in the county of Philadelphia and State of Pennsylvania, have invented and produced a new and original design for a pattern to be inwrought in two-ply upholstery tapestry or damask woven with two warps and two wefts, in such colors as may be desired; and I do hereby declare that the photographic print accompanying this specification conveys to any one skilled in the art of weaving upholstery tapestry and damask a clear understanding of the same, and is sufficient to enable such persons to use my invention.

What I claim as my invention, and desire to secure by Letters Patent, is—

The design for upholstery tapestry or damask, as shown in the photographic print accompanying this specification.

JAMES E. KERR.
